UNITED STATES PATENT OFFICE.

JOSEPH STANISLAWSKI, OF HAMMOND, INDIANA.

WIRE-CUTTING ATTACHMENT FOR BAYONETS.

1,268,172.

Specification of Letters Patent.

Patented June 4, 1918.

Application filed February 19, 1918. Serial No. 218,637.

To all whom it may concern:

Be it known that I, JOSEPH STANISLAWSKI, a citizen of the United States of America, residing at Hammond, in the county of Lake 5 and State of Indiana, have invented certain new and useful Improvements in Wire-Cutting Attachments for Bayonets, of which the following is a specification.

The primary object of the invention is the 10 provision of a wire-cutter adapted for employment upon a bayonet or other blade for cutting wire such as a barbed wire barrier or entanglement, the device being substantially incased in the blade ready for operative adjustment for immediate use whenever required.

A further object of the invention is to provide an efficient wire-cutter employed upon a blade without materially adding to 20 the size or weight of the blade and so arranged that its presence will be unnoticed by a casual observer and the usefulness of the blade will not be impaired.

A still further object of the device is to 25 provide a wire-cutter for a bayonet adapted to be normally arranged in an inoperative position for preventing the cutter from accidentally engaging other objects but being readily positioned in its operative arrangement for quickly cutting wires and similar articles.

In the drawing:

Figure 1 is a side elevation of a bayonet arranged with my device shown in its inoperative position, a cover-plate for the mechanism being removed;

Fig. 2 is a similar view thereof with the device illustrated in its operative arrangement in the act of severing a wire;

Fig. 3 is a similar view showing an intermediate arrangement of the parts;

Fig. 4 is an edge view of the bayonet showing my device inoperatively arranged;

Fig. 5 is a transverse sectional view taken 45 upon line V—V of Fig. 2;

Fig. 6 is a perspective view of the rocker-block employed with the mechanism; and

Fig. 7 is a perspective view of the knife-cutter detached.

50 Referring more in detail to the drawing, a bayonet 10 is herein illustrated arranged with my form of wire-cutter, carried by the shank or base 11 of the bayonet adjacent the blade 12 thereof.

55 A chamber 13 is formed in the shank 11 adapted for housing the cutter mechanism

while a cover-plate 14 forming one side portion of the shank 11 is normally arranged over the said chamber. A rocker-block 15 substantially heart-shaped in form is pivoted upon a transverse pin 16 within the chamber 13 and having a slot 17 in the top edge 18 thereof, it being understood that said edge 18 may be positioned in substantially the same plane as the adjacent edge 19 of the shank 11.

A curved cutter or knife 20 is pivoted at 21 to one corner of the block 15 arranged for swinging movement within the slot 17 somewhat after the nature of a pocket-knife structure. An opening 22 is arranged for the chamber 13 in the edge 19 of the shank and the knife 20 is adapted for swinging through the said opening from its closed position as shown in Fig. 1 of the drawing 75 to its open arrangement as illustrated in Fig. 2 thereof. A leaf-spring 23 is anchored within the chamber 13 by means of an angle-iron 24 with the free end of the spring in constant contact with a projecting arm 25 carried by the block 15.

A curved abutment 26 is provided upon the shank edge 19 overlying a portion of the opening 22 and having a head 27 overlying the cutter 20 provided with a slot 28 within 85 which the adjacent outer curved edge 29 of the cutter 20 is adapted to engage when the device is operatively arranged. The cutter 20 has a heel 30 normally engaging the bottom portion 31 of the abutment 26 for sliding movement thereon during the shifting of the cutter 20.

The spring 23 normally positions the device in its operative arrangement as illustrated in Fig. 2 of the drawing by shifting 95 the block 15 with the arm 25 thereof against the heel 30 of the cutter 20 and the said heel engaging the abutment bottom 31 while the cutter 20 is seated within the slot 28 of the head 27. By thrusting the bayonet forwardly with a wire, such as 32, positioned between the inner sharpened edge 33 of the cutter 20 and the side 18 of the block 15, the pivot point 21 of the cutter will be forced rearwardly, while the engagement of the 105 outer edge 29 of the cutter with the abutment 26 will force the cutting edge 33 toward the block edge 18 thereby severing the wire 32. When the wire is severed the spring 23 automatically returns the block 15 110 and cutter 20 to their operative positions.

The block 15 has the straight side 18

thereof cut away at 34 at one side of the slot 17 for permitting freedom of movement during the operation of the parts, it being understood that the edge portion of 5 the block 35 opposite the cutaway side 34 is suitably sharpened for coöperating with the cutter edge 33. A knob 36 is provided upon the cutter 20 for convenience in retracting the cutter within the chamber 13 10 for positioning the free end 37 thereof within a keeper-notch 38 at the forward end of the chamber 13. The cutter 20 may be readily released from the notch 38 by moving the same slightly inwardly, it being understood that the spring 23 maintains the 15 cutter 20 in its engagement with the notch 38 by reason of the fact that the portion of the spring bearing upon the block 15 tends to shift the blade 20 toward the notch 28 20 while the heel 30 engages the abutment face 31. When the device is inoperative as illustrated in Fig. 1, the same is substantially concealed from view but is readily shifted by engaging the knob 36 for positioning the 25 cutter 20 ready for use in cutting wires.

What I claim as new is:

1. In combination with a bayonet having a chamber, pivotally connected cutters pivotally mounted within the chamber, resilient means adapted for normally positioning one of the cutter members exteriorly of the chamber, and an abutment overlying the said last-named cutter member for engagement therewith during the movement 35 of the cutter members toward each other in the cutting operation.

2. In combination with a bayonet having a shank formed with a chamber with a side opening for the chamber, a block pivoted 40 in said chamber having a slot upon one side thereof and with a cutting edge formed upon the portion of the block on one side of the slot, and a knife pivoted to said block having a sharpened edge adapted for coöperating 45 with the aforementioned cutting edge in the cutting operation.

3. In combination with a bayonet having a shank formed with a chamber with a side

opening for the chamber, a block pivoted in said chamber having a slot upon one side 50 thereof and with a cutting edge formed upon the portion of the block on one side of the slot, a knife pivoted to said block having a sharpened edge for coöperating with the aforementioned cutting edge in the cutting 55 operation, resilient means engaging the said block adapted for normally maintaining the knife projected through the said opening, and an abutment upon the shank in contact with the adjacent side of the knife 60 during the retraction of the knife within the chamber whereby the knife is shifted into seating reception within said slot during the traversing of said cutting portions when the device is in operation. 65

4. In combination with a bayonet having a shank formed with a chamber with a side opening for the chamber, a block pivoted in said chamber having a slot upon one side 70 thereof and with a cutting edge formed upon the portion of the block on one side of the slot, a knife pivoted to said block having a sharpened edge for coöperating with the aforementioned cutting edge in the cutting 75 operation, resilient means engaging the said block adapted for normally maintaining the knife projected through the said opening, an abutment upon the shank in contact with the adjacent side of the knife 80 during the retraction of the knife within the chamber whereby the knife is shifted into seating reception within said slot during the traversing of said cutting portions when the device is in operation, the shank being arranged with a keeper-notch 85 at the front end of the chamber adapted for receiving the free end of the knife in its inoperative position, a hand hold knob upon the outer edge of the knife, and a heel at the opposite end of the knife 90 adapted for slidably engaging the bottom of said abutment during the shifting of the block.

In testimony whereof I affix my signature.

JOSEPH STANISLAWSKI.
